VERNIER-TYPE OIL BURNER NOZZLE

Nicholas F. Martin, Wilmington, Del.

Application September 20, 1949, Serial No. 116,717

2 Claims. (Cl. 299—136)

2

This invention relates to control valves, and more particularly to a device for controlling the flow of liquid fuel in an oil burner.

A main object of the invention is to provide a novel and improved oil burner control device which is very simple in construction, which is easy to manipulate, and which provides accurate control of the size of the spray orifice of an oil burner.

A further object of the invention is to provide an improved control valve for controlling the size of the jet of fuel in a marine oil-burning boiler or similar oil-burning device, the control device involving only a few parts, being reliable in operation, and providing a visual indication of the rate of flow of fuel to the burner orifice at all times.

Further objects and advantages of the invention will become apparent from the following description and claims, and from the accompanying drawings, wherein:

Figure 1 is a front end elevational view of a calibrated oil burner fuel jet device constructed in accordance with the present invention;

Figure 2 is a longitudinal cross-sectional view taken on the line 2—2 of Figure 1;

Figure 3 is a transverse cross-sectional view taken on the line 3—3 of Figure 2;

Figure 4 is a fragmentary elevational view of the rear end portion of the calibrated jet device, showing the calibrated scale and the pointer associated therewith.

Referring to the drawings, 11 designates the body of the burner, said body being generally cylindrical in shape, and being formed with an oil-supply conduit 12 through which fuel oil may be admitted into the body 11. Threaded on the forward end of the body 11 is a sleeve member 13, the body 11 being formed with an annular shoulder at 14 and a plurality of annular shims 15 being interposed between the shoulder 14 and the rim of the sleeve 13 to provide a desired position of the sleeve 13 with respect to the body 11. The sleeve 13 may be provided with indentations 16 and the body 11 may be provided with similar indentations 17, whereby the sleeve member may be accurately positioned with respect to body 11 by aligning the indentations 16 with the indentations 17. Threaded on the forward end of the sleeve member 13 is a nut 18 carrying a conically-apertured plate 19, the aperture in the plate 19 being centrally located and defining the outer wall of the fuel-discharge opening. Plate 19 is recessed, as shown at 20, and sleeve member 13 is formed with longitudinal passages 21, whereby 22 the body 11

the recess 20 is placed in communication with the inside of the body 11. The bore of sleeve member 13 is designated at 22, said bore being formed with a longitudinal keyway 23. Designated at 24 is a stem formed at its forward end with a needle valve portion 25 received in the conical aperture of plate 19 and formed with annular ribs 26 slidably fitting the bore 22. Each rib 26 is formed with a lug 27 slidably fitting the keyway 23 and preventing rotation of the stem 24.

Threaded on the rear end of the body 11 is a nut 28 formed with an annular recess 29 receiving the flange 30 of a sleeve member 31. The sleeve member 31 is secured in the position shown in Figure 2 by a nut 32 rotatably surrounding said sleeve member and threaded into the nut 28. The sleeve member 31 is thereby held against longitudinal movements with respect to nut 28, but is freely rotatable in said nut. The valve stem 24 is formed with a reduced extension 33 which is threadedly engaged with the sleeve member 31. Designated at 34 is a cylindrical cup member which fits over the end of the nut 28 and is rigidly clamped to the sleeve member 31 by a bolt 35 threaded into the end of the sleeve 31, a washer 36 being interposed between the head of the bolt and the inner wall of an annular, axial recess 37 formed in the cup member 34. A locking pin 38 positioned in opposing recesses in the cup member 34 and sleeve 31 is employed to positively couple the cup member to the sleeve member, as shown in Figure 2. Secured on the nut 28 is a stationary, longitudinally-directed pointer 39, and marked on the outer surface of the cylindrical wall of the cup member 34 is a scale 40 calibrated in terms of various sizes of fuel-discharge openings. Designated at 41 is a radially-projecting, outwardly-biased, spring-pressed detent member positioned in a radial recess formed in the nut 28 and being engageable in recesses 42 formed in the inner wall surface of the cup member 34 and spaced in accordance with the spacing of the calibration numerals of the scale 40. As shown in Figure 2, the detent 41 is longitudinally aligned with the pointer 39, whereby the various numerals on the scale 40 may be made to positively register with the pointer 39.

Designated at 43 is a flexible bellows which is threadedly secured at 44 to the valve stem 24 and which is clamped between the end of body 11 and the recess, shown at 45, in which body 11 is threadedly connected to the nut 28. The reduced stem portion 33 is thereby effectively sealed off with respect to the main internal portion of the body 11. Annular shims, such as shown at

46, may be positioned between the flared end of the bellows 43 and the annular shoulder defined at the bottom of the recess 45.

The rear end of the body 11 adjacent the nut 28 may be formed with indentations 47 and the nut 28 may be formed with similar indentations 48, whereby by aligning the indentations 47 and 48, the nut 28 may be rotated to a predetermined desired position with respect to the body 11, as previously described with respect to the indentations 16 and 17, thereby providing a means for maintaining the accuracy and original calibration of the scale 40 at all times.

It will be seen from Figure 2 that by revolving the cup member 34, the stem 24 may be advanced or retracted in the body 11 because of the threaded connection of extension 33 with the sleeve 31. This enables the needle valve element 28 to be advanced or retracted in the discharge orifice of the plate 19. The pointer 39 indicates on the scale 40 the size of the discharge orifice at any particular position of adjustment of the cup member 34. It is, therefore, apparent that the size of the orifice may be readily changed from one value to another merely by rotating the cup member 34 to bring the desired value corresponding to the desired size of orifice into registry with the pointer 39. The cup member 34 is releasably locked in adjusted position by the engagement of the detent 41 with the appropriate recess 42 in the inner wall of the cup member.

In the event that the device is taken apart for cleaning or repair, the original calibration of the scale 40 may be maintained when the device is reassembled by employing the same number of shims 15 as originally employed and by registering the indentations 16 and 17 at the forward end of the device and the indentations 47 and 48 at the rear end of the device in reassembling same.

While a specific embodiment of a calibrated fuel burner adjustable nozzle device has been disclosed in the foregoing description, it will be understood that various modifications within the spirit of the invention may occur to those skilled in the art. Therefore, it is intended that no limitations be placed upon the invention except as defined by the scope of the appended claims.

What is claimed is:

1. An adjustable liquid fuel burner nozzle comprising a hollow body having one end provided with a fuel discharge orifice, a valve stem positioned longitudinally within said body and slidably and non-rotatably supported in the latter for longitudinal movement, the end of said valve stem contiguous to said orifice being provided with a needle valve portion receivable within said discharge orifice upon longitudinal movement of said valve stem toward said one end of said body, a sleeve member positioned contiguous to the other end of said body and mounted on the latter for rotary movement about the longitudinal axis of said valve stem, an extension carried by the other end of said valve stem and threadedly engaging said sleeve member for effecting the longitudinal movement of said valve stem in response to the rotary movement of said sleeve member, a cylindrical cup member disposed axially of said sleeve member and fixedly secured thereto, the outer periphery of said cup member being provided with a scale including

circumferentially spaced indicia, an index element carried contiguous to said scale and cooperating with said spaced indicia for indicating the position of said needle valve portion with respect to said discharge orifice, the inner periphery of said cup member being provided with recesses circumferentially spaced at intervals corresponding to the spacing of said indicia, and a spring biased lug projecting outwardly of said body and selectively engageable with said recesses for detachably securing said cup member to said body in select positions of the rotary movement of said cup member.

2. An adjustable liquid fuel burner nozzle comprising a hollow body having one end provided with a fuel discharge orifice, a valve stem positioned longitudinally within said body and slidably and non-rotatably supported in the latter for longitudinal movement, the end of said valve stem contiguous to said orifice being provided with a needle valve portion receivable within said discharge orifice upon longitudinal movement of said valve stem toward said one end of said body, a sleeve member positioned contiguous to the other end of said body and mounted on the latter for rotary movement about the longitudinal axis of said valve stem, an extension carried by the other end of said valve stem and threadedly engaging said sleeve member for effecting the longitudinal movement of said valve stem in response to the rotary movement of said sleeve member, a cylindrical cup member disposed axially of said sleeve member and fixedly secured thereto, the outer periphery of said cup member being provided with a scale including circumferentially spaced indicia, an index element carried contiguous to said scale and cooperating with said spaced indicia for indicating the position of said needle valve portion with respect to said discharge orifice, the inner periphery of said cup member being provided with recesses circumferentially spaced at intervals corresponding to the spacing of said indicia, a spring biased lug projecting outwardly of said body and selectively engageable with said recesses for detachably securing said cup member to said body in select positions of the rotary movement of said cup member, and a flexible sealing means circumscribed about said extension and fixedly secured to said other end of said stem and said sleeve member.
